UNITED STATES PATENT OFFICE.

WHITFIELD AUSELONE FAUCETT, OF RALEIGH, NORTH CAROLINA.

PRINTER'S GALLEY.

SPECIFICATION forming part of Letters Patent No. 727,924, dated May 12, 1903.

Application filed February 12, 1903. Serial No. 143,017. (No model.)

To all whom it may concern:

Be it known that I, WHITFIELD AUSELONE FAUCETT, a citizen of the United States, and a resident of Raleigh, in the county of Wake and State of North Carolina, have invented a new and Improved Printer's Galley, of which the following is a full, clear, and exact description.

This invention relates to printers' galleys, ordinarily employed for the reception and temporary holding of type-set matter or typed composition in line blocks, such as is produced by a linotype-machine, and has for its object to provide a galley of novel simple construction which will securely hold in proper condition type-set matter that is subsequently transferred to the imposing bed or "stone" for "make-up" into "form" by keying such matter in columns within a chase, a further object being to provide measuring-scales for the improved galley which will accurately show the length of a "slug" of type-set matter at a glance, and thus facilitate the making up of a column of predetermined length by avoiding the necessity of applying a measuring-stick or rule thereto.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a perspective view of the improved galley. Fig. 2 is an enlarged partly-sectional plan view of a portion of the galley and of an adjustable slide-block thereon substantially on the line 2 2 in Fig. 3, and Fig. 3 is an enlarged transverse sectional view substantially on the line 3 3 in Fig. 1.

The galley is to be proportioned to suit the dimensions of type employed in the composition of literary matter that is to be held in the galley and may be constructed of any suitable material.

The bottom-piece or bed of the galley (designated by the numeral 5) is of a suitable length and width rectangular peripherally and having a true level upper surface. On the side edges of the galley-bed 5 two similar

border-ledges 6 are erected, which at their normal upper ends are joined by the transverse head-strip 6^a, the ledges and head-strip having sufficient height to afford proper lateral support to the type-set matter that the galley receives. Along the inner side surface of each ledge 6 a series of evenly-spaced indentations *a* is formed therein, these indentations being disposed oppositely in pairs and, as represented in Fig. 2, are formed as ratchet-teeth that incline away from the head-strip 6^a.

Upon the bed-piece 5 a slide-block 7 is seated and adapted for longitudinal adjustment thereon, means being provided to hold said block at a desired point secured to the ledges 6 in a manner which permits its release and change in position along on the bed-piece 5, as occasion may require.

One convenient and simple means is preferably employed for a changeable retention of the slide-block 7 on the bed-piece 5, and comprises the details shown in Figs. 2 and 3, constructed as follows: A rectangular form is preferably given to the slide-block 7, its length permitting the ends thereof to nearly touch an adjacent ledge 6 when said slide-block is mounted transversely on the bed-piece 5. In the lower side of the slide-block 7 a recess is formed, the extent of which is defined by the depending flanges *b* *b'* *b*², the flanges *b* *b'* depending, respectively, from the opposite ends of the block 7 and the transverse flange *b*² from a side edge thereof, as is clearly shown in Fig. 2. A headed pivot-bolt 8 is loosely passed down through the central perforation *c* in the slide-block 7, so as to project the journal end 8^a thereof below the top wall of the block into the recess or chamber therein, the degree of downward extension of the part 8^a being defined by the flat collar 8^b, that is formed or secured on the shank of the bolt and seats upon the upper surface of the block, as is clearly shown in Figs. 1 and 3, the headed enlargement 8^c on the upper end of the bolt affording means for manipulation of the same, so as to turn it in either direction. A rock-arm 9, preferably in the form of a flat bar, is mounted upon and secured to the depending portion of the bolt 8 below and near to the flat lower side of the slide-block 7, the portion of the bolt

engaged by the rock-arm being squared and inserted through a corresponding angular aperture in the arm at its longitudinal center, whereby the rotatable movement of the bolt 8 will correspondingly move the rock-arm. The secured engagement of the bolt 8 with the rock-arm 9 at the center of the latter provides said arm with two members of equal length, and upon the ends of said members two similar locking-bars 10 are pivoted at one end of each bar, as indicated at *d* in Fig. 2. The locking-bars 10 project oppositely and pass loosely at their outer ends *e* through perforations in the side flanges *b* *b'* of the slide-block 7, these ends *e* being shaped to freely enter and occupy certain of the indentations *a*, opposite to which they may be located by the sliding movement of the block 7. A spiral spring 11 is secured by one of its ends upon one end portion of the rock-arm 9 near the pivot *d*, and at the opposite end thereof the spring is attached to one of the side flanges of the slide-block 7, and, as shown in Fig. 2, provision is made for a connection of the spring to either side flange *b* or *b'* and to either end of the rock-arm, as may be preferred. The contractile force of the spring 11 serves to slightly rock the arm 9, so as to project the ends *e* of the locking-bars 10 into appropriate indentations *a*, and thus hold the slide-block secured in place upon the ledges 6 of the galley.

Upon the upper surface of one ledge 6 a measuring-scale 12 is formed or secured that may indicate inches and fractions thereof, and on the top face of the other ledge 6 a measuring-scale 13 is affixed that may represent pica ems as a standard of measure for type-set matter placed in the galley.

In use the galley is supported on a table or other fixture, so as to be convenient and easy of access for deposit therein of slugs of type-set composition, as usual. The compositor after removing the matter from his composing-stick to the galley shoves such matter toward the head-strip 6^a of the galley by a sliding movement of the block 7, that will press the slug either against the head-strip or into contact with other matter previously placed in the galley, the shape of the indentations *a* and the ends *e* of the locking-bars 10 permitting the block 7 to receive forward adjustment and adapting the ends *e* to hold the block where it is positioned. It will be evident that the measurement of the slugs of type-set matter may be seen readily by inspection of an appropriate scale 12 or 13, and it will also be noted that the sides of the indentations *a* and the reversely retractile and locking bars 10 constitute coacting devices by which on bodily moving the block in one direction parallel with the side faces of the said ledges 6 the said block may be adjusted and secured in any desired position automatically.

It is claimed for the improvement that it facilitates the proper make-up of a page, as it enables the operator to exactly justify the

composition and arrange the matter properly for length as it is held clamped in the galley.

The provision of scales on the ledges of the galley is very advantageous for the proper disposition of advertisements in a column or page, as it enables the measurement of such matter before placing it on the imposing-stone to make up a page.

The improved galley enables the proper retention of slugs of type-set matter even of a few lines in length for taking a proof-slip therefrom, and corrections may be made, if necessary, without danger of knocking the matter into "pi."

The improvement is obviously of advantage to the job-printer by enabling the accurate measurement of the job in pica "ems" to quickly determine the space and cost, and in case the matter is set in "linotype" the successive lines may be held for proof-printing and for justifying in a very convenient manner by means of the adjustable slide-block that is a detail of the invention.

Having thus described my invention, I claim as new and desire to secure by Letters Patent—

1. A printer's galley, comprising a bed-piece, side ledges thereon, a head-strip, a slide-block mounted transversely on the bed-piece, and coacting devices by which the said block may be adjusted and secured in place automatically on bodily moving the same in one direction parallel with the sides of said ledges.

2. A printer's galley, comprising a bed-piece, side ledges thereon, each having spaced indents on the inner sides thereof, a head-strip joining said ledges, a slide-block and adjustable locking-bars, together with devices co-operating therewith, whereby the said block may be adjusted and secured in position automatically on moving the same bodily toward the head-strip in parallelism with the sides of said ledges.

3. A printer's galley, comprising a flat oblong bed-piece, parallel side ledges thereon, each ledge having a series of spaced indents on its inner side, a rectangular slide-block recessed on its lower side, spring-pressed locking-bars working through openings in the side flanges of the slide-block, and means for retracting said locking-bars, the organization being such that the said block may be adjusted and secured in place automatically on bodily moving the same in one direction parallel with the sides of said side ledges.

4. A printer's galley, comprising a bed-piece, side ledges thereon, a head-strip, a slide-block mounted transversely on the bed-piece, and coacting devices by which the said block may be adjusted and secured in place automatically, by bodily moving the same in the direction of the head-strip and parallel with the sides of said ledges, one of the latter being provided with a measuring-scale graduated in units of lineal measurement.

5. A printer's galley, comprising a bed-

piece, side ledges thereon, a head-strip, a slide-block mounted transversely on the bed-piece, and coacting devices by which the said block may be adjusted and secured in place 5 automatically on bodily moving the same toward the head-strip in parallelism with the sides of said ledges, one of said ledges being provided with a measuring-scale graduated in units and fractions thereof, and the other

provided with a similar scale graduated to 10 represent pica ems as a measure of length.

In testimony whereof I have signed my name to this specification in the presence of two subscribing witnesses.

WHITFIELD AUSELONE FAUCETT.

Correction in Letters Patent No. 727,924.

Affidavit having been filed showing that the name of the patentee in Letters Patent No. 727,924, granted May 12, 1903, for an improvement in "Printers' Galley," should have been written and printed *Whitfield Anselone Faucett* instead of "Whitfield Auselone Faucett," it is hereby certified that the proper correction has been made in the files and records pertaining to the case in the Patent Office, and should be read in the Letters Patent that the same may conform thereto.

Signed and sealed this 23d day of June, A. D., 1903.
